UNITED STATES PATENT OFFICE

EDWIN A. LEE, OF PHILADELPHIA, PENNSYLVANIA

METHOD OF AND MEANS FOR PACKING THIN FABRICS TO PREVENT WRINKLING
THEREOF

Application filed October 23, 1928. Serial No. 314,417.

My invention relates to a new and useful method of and means for packing articles of merchandise to prevent the formation of wrinkles therein, and more particularly to means for preventing the wrinkling of such articles as hosiery and the like when the latter are folded and packed in the usual manner.

It is the practice in packing stockings and delicate articles, such as hosiery and the like, for shipment, to place the desired number of folded stockings or other similar articles in a box; said stockings being usually wrapped in ordinary tissue paper. When a box containing a number of stockings is handled in shipment and in stock, the stockings contained therein are liable to wrinkle and get out of shape when the box is set on its vertical edge, is dropped, or is otherwise roughly handled or maintained in any but the horizontal position. This wrinkling of the stockings destroys their fresh appearance and gives them the appearance of being previously handled, and generally detracts from their initial attractive appearance and salability.

It is therefore the object of my invention to provide means for packing any desired number of stockings or similar articles in a box, whereby said stockings are retained in their original condition or appearance and prevented from wrinkling regardless of the position of the box in which they are contained or the manner in which said box is handled.

To the above ends my invention consists of an especially designed corrugated, wrinkled, or roughened spacer or partition such as a sheet of cardboard or the like, which when inserted between each successive pair of stockings contained in a box will protect the latter against wrinkling by the engagement of the folded stockings with the contiguous roughened wall of said cardboard spacer.

For the purpose of illustrating my invention I have shown in the accompanying drawings one form thereof which is at present preferred by me, since the same has been found in practice to give satisfactory and reliable results, although it is to be understood

that the various instrumentalities of which my invention consists can be variously arranged and organized and that my invention is not limited to the precise arrangement and organization of the instrumentalities as herein shown and described. 55

In the drawings:

Figure 1, represents a plan view of the cardboard spacer detached embodying my invention. 60

Figure 2, represents a perspective view of a box containing stockings and provided with my novel cardboard spacer interposed between each pair of stockings or the like.

Figure 3, represents a section on line 3—3 of Figure 1. 65

Referring to the drawings, in which similar numerals of reference indicate corresponding parts, 1 designates my novel spacer comprising a sheet of cardboard or the like 70 having a body 2 provided with the transverse spaced creases or ribs 3 positioned on opposite sides thereof. 4 designates a box or container of any conventional construction having the bottom 5, side walls 6, and top or lid 75 7 which may be hinged at the right hand edge if desired. 8, 9 and 10 designate lower, intermediate and upper stockings or pairs thereof respectively folded and placed flat within said box. Between the lowermost pair of 80 stockings 8 and the intermediate pair of stockings 9, and between the intermediate pair of stockings 9 and the upper pair 10 I place spacers 1 collocated as will be understood from Figure 2. If desired or found 85 necessary I may also place a spacer 1 in the bottom of the box, that is, below the lower pair of stockings 8; and another at the top of the box, that is above the pair of stockings 10. 90

It will further be seen that while the creases or corrugated ribs 3, formed in the body of the spacer 1 project sufficiently to engage the fabric of the stocking to prevent wrinkling, said ribs are nevertheless not 95 sharp or rough enough in any way to mar or damage the fabric. The inclined walls 11 formed between the successive reversed creases 3 serve as yielding bearings or pressure members which apply a certain amount 100

of slight squeezing pressure to the contiguous stocking, so that the pressure or supporting effect is distributed uniformly throughout the area of the entire stocking.

5 When the stockings are thus packed in the box and interspersed with the novel spacers 1 shown in Figure 1 the creases or ribs 3 on the opposite surfaces of said spacers engage the adjacent, contiguous walls or surfaces of the folded stockings 8, 9, and 10, so that when the box 4 is shaken, dropped, stood on edge or otherwise roughly handled said stockings are retained by the contiguous roughened surfaces of the spacers 1, and are 10 prevented from wrinkling or from otherwise becoming displaced thereby enabling the stockings or other articles constantly to retain their normal, properly folded condition, and to preserve their fresh and neat appearance when ultimately presented to purchasers 15 at retail stores.

There is great need in the hosiery business for means which would preserve the sheer, thinly woven stockings in a neat, smooth folded condition and to the above ends various expedients have been resorted to, but heretofore no adequate means for attaining this object have been devised.

It will be seen that by this novel method of 20 packing thinly woven, sheer stockings or other similar fabrics in a box or container, such stockings or fabrics are always maintained in their proper folded position and are positively protected from any danger of slipping and wrinkling with the consequent attendant disadvantages.

While I have described the spacer sheet 1 as being preferably of cardboard, it may be 25 of any other suitable material and while the creases seen in Figure 1 are shown as being preferably arranged in parallelism or in horizontal alignment, they can be otherwise disposed, as it is only necessary that the opposite surfaces of the spacer 1 be provided with 30 ridges, corrugations, or the like substantially as seen in Figure 3 so that a single spacer can function with respect to a pair of stockings on either side thereof, to retain them in a flat and unwrinkled condition as they 35 appeared when initially packed. The creases or ribs 3 with their coacting inclined walls are formed by any suitable pressing or stamping means, which preferably does not sever the spacer body, but leaves the inclined transverse bars or walls and ribs substantially as 40 seen in Figure 3. The bars 11 of the spacers preferably extend transversely to the length of the hosiery.

While I have described my invention as particularly applicable to packing hosiery, it is 45 equally applicable to packing other thin delicate fabrics as handkerchiefs, rayon underwear and the like.

I am aware that the invention may be embodied in other specific forms without de-

parting from the spirit or essential attributes thereof, and I therefore desire the present embodiment to be considered in all respects as illustrative and not restrictive, reference being had to the appended claims rather than to the foregoing description to indicate the scope of the invention.

Having thus described my invention, what I claim as new and desire to secure by Letters Patent, is:—

1. A spacer for preventing packed textile articles from wrinkling and displacement, which comprises a body sheet having transverse oppositely disposed resilient ribs pressed therefrom, said ribs being joined to said body sheet by inclined bars, causing a slight tension to be exerted at intervals on the contiguous textile articles.

2. Means for preventing hosiery from wrinkling, comprising a container, pairs of stockings therein, and a spacer contiguous to each stocking, said spacer being provided with transverse resilient ribs projecting from the opposite surface thereof contiguous to the fabric of the juxtaposed stocking, said ribs being joined to said spacer sheet by inclined integral bars which cause said ribs frictionally to engage at intervals the contiguous fabric.

3. A spacer for preventing packed textile articles from wrinkling and displacement, which comprises a body sheet having transverse oppositely disposed parallel resilient ribs pressed therefrom, said ribs being joined to said body sheet by inclined bars thereby causing a slight tension to be exerted at intervals on the contiguous textile articles, the parallel surfaces between each pair of resilient ribs being smooth and unbroken.
